UNITED STATES PATENT OFFICE.

WALTER E. DONELSON, OF CONWAY, MASSACHUSETTS.

BUSHING-REMOVER.

1,338,495.

Specification of Letters Patent.

Patented Apr. 27, 1920.

Application filed September 8, 1919. Serial No. 322,487.

To all whom it may concern:

Be it known that I, WALTER E. DONELSON, a citizen of the United States, residing at Conway, in the county of Franklin and 5 State of Massachusetts, have invented certain new and useful Improvements in Bushing-Removers, of which the following is a specification.

This invention relates to improvements in 10 bushing removers.

An important object of the invention is to provide a device of the above mentioned character, simple in construction and cheap to manufacture.

15 A further object is to provide a device of the above character which may be used for removing bushings of different sizes, within a certain range.

20 A further object is to produce such a device which may be used with a standard socket wrench or any of the adjustable wrenches now upon the market.

Other objects and advantages will appear 25 throughout the course of the following discussion.

In the accompanying drawings, wherein for the purpose of illustration, is shown the preferred embodiment of my device,

Figure 1 is a side elevation of my bushing 30 remover in use to remove a bushing, a portion of one end of the remover being shown in section for the purpose of clarity.

Fig. 2 is a section taken on a line 2—2 of Fig. 1, and

35 Fig. 3 is a section taken through the bushing remover and shown enlarged to more clearly illustrate the peculiar construction of the teeth thereof.

40 Referring now more particularly to the drawings, numeral 10 indicates the body portion of my device. This body portion as clearly shown in Fig. 1, is tapered throughout its length and provided with longitudinal grooves 11 after the manner of 45 a tap.

The exterior of the body portion is provided with screw threads 12 of the same depth throughout the body portion. These threads, as clearly shown in Fig. 3, are

50 of a peculiar construction, the upper sides of the threads or the side remote from the entrance end of the remover being substantially at right angles to the axis of the body portion as indicated at 13, while the under sides of the threads or the sides adja-

cent the entrance end are inclined at an angle of approximately 45° to the axis as indicated at 14. The outer faces of the threads are not carried to a point as is usual in a finished tap thread, but are flattened in 60 the plane of the taper of the body portion, so as to give considerable surface upon the outer face of the thread.

The smaller end 16 of the remover is provided with a driving face 17 which is concaved to receive the end of a bolt drift or the like to drive the remover out after it is seated in position. The larger end of the remover is slightly reduced in size and provided with squared shank 18 adapted to receive 70 a wrench or the like.

The operation of my device is as follows:

The remover is inserted into the bushing and screwed in until it attains a firm grip in the metal. Because of the peculiar construction of the threads, these threads while cutting into the metal have a tendency to bind and after the threads have attained a sufficient grip in the metal to remove the bushing, it becomes almost impossible to 80 turn the remover by the use of an ordinary hand wrench. The squared upper surfaces of the threads give a flat firm engagement against the metal of the bushing and therefore have a very solid grip when being 85 driven. As is well known the metal used for bushings is generally bronze or brass and is consequently very soft, and if these threads had the taper ordinarily applied to the teeth of a tap, driving upon the end 90 would have a tendency to swage the metal and flatten it out so that the threads would drive loose from their engagement with the bushing.

It will be understood that as many 95 changes are possible in the shape, size, and arrangement of the various parts of my device without departing from the spirit of the invention, I do not limit myself to specific constructions herein shown and described, but may make any such changes without departing from the spirit of the invention or scope of the subjoined claims.

What I claim is:

1. In a bushing remover a tapered body 105 portion provided with longitudinal slots, screw threads formed upon said body portion, said threads being of the same depth throughout the length of said body portion, the faces of said threads remote from the

entrance end of said body portion being at substantially right angles to the axis thereof.

2. In a bushing remover, a tapered body portion provided with screw threads of the same depth throughout the length thereof and having longitudinal clearance slots, the faces of said threads remote from the entrance end of the body portion being substantially at right angles to the axis of said body portion and the outer faces of said threads being provided with flattened surfaces parallel to the plane of taper of the body portion, the entrance end of said body portion being provided with a driving face.

3. In a bushing remover, a tapered body portion provided with screw threads of the same depth throughout the length thereof and having longitudinal clearance slots, the faces of said threads remote from the entrance end of the body portion being substantially at right angles to the axis of said body portion, the faces of said threads adjacent said entrance end being inclined away from said entrance end at an angle of approximately 45° to the axis of said body portion and the outer faces of said threads

being provided with flattened surfaces parallel to the plane of taper of the body portion.

30

4. A bushing remover, comprising a tapered body portion provided throughout its length with threads of uniform depth, said body portion being provided upon one end with a driving face and upon the other end with a squared shank, longitudinal slots formed in said body portion, the faces of the threads upon said body portion remote from the entrance end thereof being substantially at right angles to the axis of the body portion, the faces of the threads adjacent said entrance end being inclined away from said entrance end at an angle of approximately 45° to the axis of said body portion, and the outer faces of said threads being provided with flattened surfaces lying in a plane parallel to the plane of taper of said body portion.
